UNITED STATES PATENT OFFICE.

ROBERT W. BOSTWICK, OF DETROIT, MICHIGAN.

WINDOW-REGULATOR LOCK.

Application filed September 24, 1923. Serial No. 664,558.

To all whom it may concern:

Be it known that I, ROBERT W. BOSTWICK, a citizen of the United States of America, residing at Detroit, in the county of Wayne 5 and State of Michigan, have invented certain new and useful Improvements in Window-Regulator Locks, of which the following is a specification, reference being had therein to the accompanying drawings.

10 The invention relates to window regulators designed particularly for use in motor vehicles and refers to a lock for holding the window in its adjusted position. One of the objects of the invention is the provision 15 of a window regulator lock which holds the gear for actuating the window from rotation in either direction and which is released by the means for rotating the gear in either direction to raise or lower the window. 20 Another object is the provision of a simple construction of lock which may be cheaply manufactured and which occupies but small space.

With these as well as other objects in 25 view, the invention resides in the novel features of construction, combinations and arrangements of parts as more fully herein-after set forth.

30 In the drawings: Figure 1 is an inside elevation, partly broken away, of a motor vehicle door with my invention applied;

Figure 2 is a cross section on the line 2—2 of Figure 1;

35 Figures 3 and 4 are cross sections respectively on lines 3—3 and 4—4 of Figure 2.

40 1 is the lock board of a motor vehicle door and 2 the window vertically slidably engaging in guideways in the hinge and lock upright members or posts of the door. The window regulator for raising and lowering the window, as shown in the present instance, comprises the flexible rack 3 connected near its lower end to the window and driven by means of a driving gear 4 upon the inner side of the lock board 1.

45 For locking the window in its various adjusted positions, I have provided a positive lock for holding the driving gear 4 from rotation in either direction. This lock is controlled by a rotatable handle 5 which also controls the raising and lowering of the window. In detail, the lock comprises 55 the ratchet wheel 6, the teeth of which are engageable by the pawls 7 and 8 pivotally

mounted intermediate their ends upon the disk 9 which is secured to the shaft 10 of the driving gear by means of the transverse pin 11 extending through the shaft and engaging in diametrically opposite radial slots 12 in the disk. 13 is a U-shaped spring embracing the shaft 10 and having its opposite ends engaging the pawls 7 and 8 to force their noses outwardly and into engagement with the teeth of the ratchet wheel. The arrangements of pawls is such that their noses engage teeth upon the ratchet wheel at opposite sides of the shaft 10 and as a consequence each pawl holds the shaft and consequently the driving gear 4 from rotation in one direction. Since the pawls engage teeth, the locking of the driving gear from rotation in either direction is positive.

50 For the purpose of alternately releasing the pawls from engagement with the teeth of the ratchet wheel, I have provided the release member 14 secured to the shaft 15 of the handle and provided with the transverse pin 16 engageable between the free ends of the pawls 7 and 8. With this arrangement, when the handle 5 is rotated the release member will also be rotated and its transverse pin will engage either the one pawl or the other, depending upon the direction of rotation, to rock that pawl about its pivot and disengage its nose from the teeth of the ratchet wheel.

55 Continued rotation of the handle in the same direction will then rotate the driving gear 4 in the same direction through the pawl, the disk upon which the pawl is mounted, and the transverse pin connecting the disk to the shaft of the driving gear. The face of each driving pawl adjacent to 60 the spring 13 is spaced sufficiently therefrom when the pawl is in engagement with the teeth of the ratchet wheel to permit the pawl to be rocked out of engagement with the teeth, at which time the face will engage the spring for preventing any further rocking movement from taking place and also preventing the free end of the pawl 65 from coming into engagement with the teeth of the ratchet wheel while the driving gear is being rotated from the handle. While one of the pawls is retained disengaged from the ratchet wheel, the nose of the other pawl is sliding over the teeth of the ratchet wheel, and as soon as rotation of the handle is stopped, the pawl previously disengaged from the ratchet wheel is returned 70

to its normal position by the spring 13 to cooperate with the other pawl in holding the window from either raising or lowering unless actuated by the handle.

5 To provide a construction which is comparatively cheap to manufacture and which provides bearings for the driving gear shaft and handle shaft, the casing for the pawls 7 and 8 and associated disk 9 comprises 10 the centrally recessed disk 17, the centrally apertured disk 18, and the ratchet wheel 6 therebetween and concentric therewith. These disks and ratchet wheel are rigidly secured to the plate 19 upon the inner side 15 of the lock board 1 by means of the rivets 20. The central recess in the disk 17 is of a size to receive the disk 9 and the central opening in the disk 18 is of a size to receive the annular radially extending flange 21 of 20 the release member 14, the arrangement affording journal bearings for the disk and release member. Since the release member has a cylindrical flange 22 sleeved over the inner end of the handle shaft 15 and secured thereto by a transverse pin, and since the handle shaft is journalled in the escutcheon 23, it is maintained in proper axial position. The driving gear shaft in addition to being journalled in the disk 17 is journalled in the 25 release member in axial alignment with the handle shaft. The pawls 7 and 8, disk 9, ratchet wheel 6, disks 17 and 18 and release member 14 are preferably formed of stampings.

35 What I claim as my invention is:

1. The combination with a gear rotatable in opposite directions for raising and lowering a window, of a stationary ratchet wheel, a disk between said ratchet wheel and gear 40 and connected to the latter, pivoted pawls

upon said disk and engageable with the teeth of said ratchet wheel on opposite sides of its axis, means for yieldably forcing said pawls into engagement with the teeth, and an operating member having an alternative 45 driving contact with the free ends of said pawls for releasing either of said pawls and subsequently rotating said gear in either direction through the released pawl and said disk.

2. The combination with a gear rotatable in opposite directions for raising and lowering a window, of a casing including a ratchet wheel, a disk rotatably mounted within said casing, pawls pivoted upon said disk and engageable with the teeth of said ratchet wheel, a shaft for said gear journalled in 50 said casing and connected to said disk, and an operating member journalled in said casing and adapted to have an alternative driving engagement with said pawls for releasing the same and subsequently rotating said gear.

3. The combination with a member movable in opposite directions for raising and lowering a window, of a stationary casing including a ratchet wheel, a disk engaging and rotatably mounted within said casing, pawls carried by said disk and engageable with the disk of said ratchet wheel, a release member engaging and rotatably mounted in said casing, a projection upon said release member alternatively engageable with the free ends of said pawls, a shaft for 55 said gear wheel journalled in said casing and release member and connected to said disk, and a handle secured to said release member.

In testimony whereof I affix my signature.

ROBERT W. BOSTWICK.
